SUCTION NOZZLE

Gustaf Einar Lofgren, Rye, N. Y., assignor to
Electrolux Corporation, Dover, Del., a corpora-
tion of Delaware

Application May 19, 1934, Serial No. 726,439

12 Claims. (Cl. 15—155)

5 My invention relates to nozzles for vacuum cleaners and more particularly to what I term upholstery nozzles. Nozzles so termed are not limited to upholsteries but are so termed to distinguish them from other nozzles, particularly floor nozzles. The type of nozzle to which this invention relates is a comparatively small nozzle.

10 The principal object of my invention is to provide a nozzle of the kind referred to incorporating means to readily pick up certain threads or hairs, such as dog hairs or lint, which are difficult to pick up with an ordinary nozzle. Another object is to provide a novel and superior construction of the type of tool in question.

15 The invention will be understood by reference to the accompanying drawings showing several forms of the invention, and which are to be considered a part of this specification, and of which:

Fig. 1 is a front view of a nozzle embodying the 20 invention;

Fig. 2 is a cross-sectional view taken on the line 2—2 of Figs. 1 and 4;

Fig. 3 is a bottom view of the nozzle;

Fig. 4 is a sectional view taken on the line 25 4—4 of Figs. 2 and 3;

Fig. 5 is a perspective view of the nozzle;

Fig. 6 shows part of a second embodiment of the invention and is a front view;

Fig. 7 is a sectional view taken on the line 30 7—7 of Fig. 6;

Fig. 8 is a top view of another part of the nozzle adapted to be secured to the part shown in Figs. 6 and 7;

Fig. 9 is a cross-sectional view taken on the 35 line 9—9 of Fig. 8;

Fig. 10 is a detail view taken in the direction 10—10 with respect to Fig. 8; and

Fig. 11 is a cross-sectional view similar to Fig. 7, but with the part shown in Figs. 8 through 40 10 secured in place.

Referring to the embodiment shown in Figs. 1 to 5, the nozzle includes a shank 10 of generally tubular form and adapted to fit onto the end of a hose connected with a source of suction, such 45 as a unit including a dust bag, a fan and a motor. Front and back walls 11 and 12 and end walls 13 extend downwardly from the shank and are flared outwardly to form an elongated mouth portion. The walls 11 and 12 may be parallel 50 as shown.

A bridge piece 14 is centrally disposed and extends between walls 11 and 12. The bridge piece may be integral with the walls 11 and 12. Centrally disposed in the bridge piece is a vertical 55 passage 16. The lower edge of this passage is

substantially in line with the contacting edge 17 of the nozzle. Passage 16 is in alignment with the internal passage of the shank portion 10. The bottom of passage 16 forms a small nozzle opening. This nozzle is preferably round.

5 The bridge piece 14 divides the lower part of the space interior of the nozzle so as to form two lateral elongated openings 18. The lateral openings and the passage 16 communicate centrally with the passage within the shank portion. 10 Grooves 19 are formed in the lower surface of the nozzle in the bridge piece 14 and extend to the outer edges as shown in Fig. 1. These grooves allow flow of air laterally of the nozzle in contact with the surface of the piece to be cleaned 15 and thereabout and this flow is tangential with respect to the opening at the bottom of passage 16. Due to the tangential grooves 19, air is drawn tangentially into the passage 16 and creates a rotary movement of air above the surface to be 20 cleaned, whereby threads are twisted and spun and are picked up due to the cyclone movement of the air. The passage 16, being directly in line with the center passage of the shank portion 10, is subject to intense suction. A single opening, 25 such as 16, does not cover much surface and, therefore, the elongated openings permit removal of dust from a relatively large surface while the central portion can be run over any part of the surface to be cleaned having threads or the like 30 sticking thereto.

The entire nozzle may be cast in one piece as in this embodiment and may be made, for example, of aluminum.

In the embodiment shown in Figs. 6 through 35 11, the nozzle is made in two parts, each part being stamped from sheet metal. As is shown particularly in Figs. 6 and 7, the upper body part 20 has a cylindrical portion 21 which is adapted to be secured to one end of a suction 40 hose. Cylindrical portion 21 communicates with a flared portion 22 which is formed with an elongated suction opening 23. The material of the body portion 20 is flared outwardly around opening 23 to form a lip 24 which lies substantially in the plane of the opening. Notches 25 are formed in the central part of the body member 20 adjacent to the lower edge thereof.

A bottom member 26 is likewise stamped from sheet metal so as to have two elongated openings 27 adjacent to either end thereof. The bottom member comprises a rim portion 28 around the outer periphery of which is formed a flange 29 at right angles to the rim portion. Rim portion 28 is also provided with upstanding flanges 30 50 55

which surround the two sides and outer ends of the elongated openings 27.

Openings 27 are separated by a central bridge piece 31, which connects opposite sides of rim portion 28, the center of the bridge piece being stamped to form a circular passage 32. Communicating tangentially with the lower end of passage 32 are grooves 33 stamped in the bottom member. Portions of the material removed to 10 form openings 27 are bent in a rounded form, as shown at 34, so as to form smooth air passages. Outer flange 29 is wider, as shown at 35, adjacent to where the outer ends of grooves 33 extend through the flanges.

15 Fig. 11 shows the body member 20 and the bottom member 26 secured together. Flanges 30 of the bottom member fit within the elongated opening 23 formed in the body member 20 and thus position the elongated openings 27 in the bottom member in alignment with the opening 23 in the body member. The material bounding the grooves 33 fits within the notches 25 formed in the sides of the body member. Flange 29 of the bottom member is bent over lip 24 of the 20 body member and thus securely holds the two members together and prevents the leakage of air therebetween. The parts 35 of flange 29 prevent leakage of air through the notches 25 outside of grooves 33.

25 The operation of this embodiment is substantially the same as in the embodiment first described and hence need not be repeated.

Although the bottom member is shown as being permanently secured to the body member of the 30 nozzle, it is obvious that a similar bottom member could be employed in connection with an ordinary nozzle and so constructed as to be attachable and removable at will.

While I have shown and described more or less 40 specific embodiments of my invention, it is to be understood that they do not constitute restrictions of the scope thereof, which is intended to be limited only by the appended claims considered in the light of the prior art.

45 What I claim is:

1. An upholstery nozzle for vacuum cleaners, said nozzle having lateral suction openings, a central opening between, and terminating in the same plane with, said lateral openings and angularly disposed to a surface to be cleaned and of such shape that a vortex is formed on tangential admission of air thereto, a groove communicating with the atmosphere and connecting tangentially with said central opening and a common outlet communicating with said central and lateral openings.

2. An elongated upholstery nozzle for vacuum cleaners, said nozzle having outer walls and a bridge piece forming elongated lateral suction openings, said bridge piece having a round opening therein and a groove communicating with the atmosphere and connecting tangentially with said round opening, said openings and groove being in substantially the same plane and a common outlet communicating with said openings.

3. An elongated upholstery nozzle for vacuum cleaners having outer walls, a bridge piece between said walls forming with said walls two lateral elongated suction openings, said bridge piece 70 having a suction opening therein of such shape that a vortex is formed therein on tangential admission of air thereto, a groove communicating with the atmosphere and connecting tangentially with the last-mentioned opening, and a common outlet communicating with said openings.

4. The combination with an upholstery nozzle for vacuum cleaners having walls forming an elongated opening, of an attachment to be applied to the elongated opening for subdividing said opening into a plurality of openings and having a small suction opening of such shape that a vortex is formed therein on tangential admission of air thereto and having a groove communicating with the atmosphere and connecting tangentially with said small opening.

5. The combination with an upholstery nozzle for vacuum cleaners having walls forming an elongated opening, of an attachment to be applied to the elongated opening for subdividing said opening into a plurality of openings and having a small centrally disposed suction opening of such shape that a vortex is formed therein on tangential admission of air thereto and having a groove communicating with the atmosphere and connected tangentially with said small opening.

6. The combination with an upholstery nozzle for vacuum cleaners having walls forming an elongated opening, of an attachment to be applied to the elongated opening for subdividing said opening into a plurality of openings and having a small round suction opening and having a groove communicating with the atmosphere and connected tangentially with said small opening.

7. An upholstery nozzle for vacuum cleaners including a body member having walls forming an elongated opening, said walls being flared outwardly around said opening, and an elongated apertured bottom member having a flange thereon, said flange being adapted to be bent over the flared part of said body member to secure said bottom member to said body member, said bottom member having a centrally located bridge piece providing a plurality of elongated suction openings, said bridge piece being formed with a central circular suction opening and having a groove communicating with the atmosphere and tangentially communicating with said central opening.

8. As a new article of manufacture, a bottom member for a vacuum cleaner upholstery nozzle including a rim portion bounding two elongated openings each adjacent to one end thereof, a bendable flange at the outer edge of said rim portion, and a centrally located bridge piece connecting opposite sides of said rim portion and separating said elongated openings, said bridge piece having a central circular opening therethrough and said rim portion having a groove tangentially communicating with said central opening.

9. As a new article of manufacture, a bottom member for a vacuum cleaner upholstery nozzle, said member being elongated and having an elongated opening adjacent each end thereof, and having a bridge piece separating said openings, said bridge piece being formed with a circular opening therethrough and said rim portion having a groove tangentially communicating with said central opening.

10. As a new article of manufacture, a bottom member for a vacuum cleaner upholstery nozzle, said member being elongated and having an elongated opening adjacent each end thereof, and having a bridge piece separating said openings, said bridge piece being formed with a circular opening therethrough, said rim portion having a groove tangentially communicating with said central opening, and said member having means for securing it to the upper part of said nozzle.

11. As a new article of manufacture, a bottom member for a vacuum cleaner upholstery nozzle, said member being elongated and having an elongated opening adjacent each end thereof, and having a bridge piece separating said openings, said bridge piece being formed with a circular opening therethrough, said rim portion having a groove tangentially communicating with said central opening, and said member having a bendable flange for securing it to the upper part of said nozzle.
12. An upholstery nozzle for vacuum cleaners including a body member having walls forming an elongated opening, said walls being flared outwardly to form a lip around said opening, and
- 5 an elongated bottom member having an elongated opening therethrough and an inner and an outer flange thereon, said inner flange fitting within the elongated opening in said body member to position said openings in alignment and said outer flange being adapted to be bent over said lip to secure said bottom member to said body member, said bottom member having a centrally located bridge piece dividing said elongated openings into two parts, said bridge piece being 10 formed with a central circular opening and said rim portion having a groove tangentially communicating with said central opening.
